UNITED STATES PATENT OFFICE.

HARRY W. SHEEHY, OF AKRON, OHIO.

CAN-OPENER.

1,094,172.

Specification of Letters Patent. Patented Apr. 21, 1914.

Application filed January 9, 1913. Serial No. 740,973.

To all whom it may concern:

Be it known that I, HARRY W. SHEEHY, residing at Akron, in the county of Summit and State of Ohio, have invented a new and Improved Can-Opener, of which the following is a specification.

My invention relates to openers for cans and other similar kinds of receptacles and it primarily has for its object to provide a device of the character noted of a very simple and economical construction, that is a simple, durable and efficient tool, capable of being readily applied to and adjusted for cans of different sizes and which can be easily manipulated to adapt it for making a clean edge cut around the top of the can close to the body portion thereof, and without danger of cutting the operator's hand or leaving a rough edge, such as is customary with can openers of like type on the market.

With the above and other objects in view, all of which will be hereinafter referred to, my invention is a can opener in which is embodied the peculiar construction and novel arrangement of parts all of which will be first described, in detail, then be specifically pointed out in the appended claims, and illustrated in the accompanying drawings, in which:—

Figure 1 is a perspective of my can opener, the same being shown as in the operation of opening a can. Fig. 2 is a similar view thereof, and which shows its application for removing a bottle cap. Fig. 3 is a perspective view that shows how my improved device is used for prying open a can top. Fig. 4 is an inverted perspective view of my can opener. Fig. 5 is a longitudinal section thereof. Fig. 6 is a transverse section on the line 6—6 on Fig. 5. Fig. 7 is a plan view of the stamped blank that constitutes the body portion or handle of my opener, and before the same is bent to the final shape. Fig. 8 is a detail view of the combined puncher rod and rotary cutter guide, and Fig. 9 is a view of the rotary cutter.

While my invention is primarily designed for use as a can opener, it should be stated, its structure is such that it may be readily utilized for other purposes, such as removing bottle caps, prying open can lids etc.

In its practical arrangement, my can opener comprises essentially a body portion or handle, a freely adjustable rotary cutter and a combined puncturing and guide rod.

The body portion 1 is formed by stamping up the blank form (see Fig. 6) that comprises the body portion proper 1, the rear part of which has a transverse slot 2, one edge 3 of which is straight, the other edge 4 being rounded at the ends, as at 5, the reason for which will presently appear. At the forward end the blank body has a longitudinally elongated slot 6, the opposite edges of which are continued as slits 7—7, whereby to provide a transverse tongue 8 and the latter has a central curved notch 9. To the rear of the slot 6, the body 1 has an aperture 10. At the opposite edges, the body 1 is scored on the lines 11—11 whereby to provide for readily bending down the said edges to produce side flanges 12—12. The forward end of the body 1 tapers, whereby, when the opposite edges are bent down the front ends of the opposing side edges or flanges form a restricted passage 14, the reason for which will be explained. The rear end of the body is curved and is bent up to form a hook-like lip 15, the said end and the side edges of the body having such shape whereby the said body may be snugly gripped in the hand without danger of cutting the hand.

16 designates a rod, the outer end of which is bent and sharpened to form a combined guide and puncturing point 17 and the other end is bent up as at 18.

19 designates a rotary steel cutter and it includes the cutting disk 20 and a guide disk 21, the two being joined by an intervening annular tapered groove 22 that rides upon the edge of the can during the cutting operation.

In assembling the parts, the cutter disk 20 is first slid onto the rod 16, the rear end of the rod is slipped up through the aperture 10 in the body 1, and upset to form a rivet-like head 23, after which the front end is moved up into the restricted opening 14 between the front ends of the opposite side edges and held securely by compressing the said side edges around the said end of the rod, as shown, the said rod being further held rigid by bending down the tongue 8 to bring its notch 9 over the rod, (see Fig. 5).

From the foregoing taken in connection with the drawing, the complete construction of my can opener device will be readily apparent.

For opening the tops of cans, the opener is properly positioned by puncturing the can

with the pointed end of the rod 16 to allow the hook end to be slipped through the can top. The handle is then brought down flatwise on the can and the cutter is slipped out 5 to suit the diameter of the can, it being guided by reason of its annular groove riding in the outer edge of the can, the required hand pressure, being now only necessary to effect the cutting of the can top as the 10 opener is swung around.

The transverse slot with the straight and curved edges mentioned provides for conveniently using my devices for uncapping bottles (see Fig. 2) and since the rear end 15 of the handle terminates in an upturned lip, the device can also be freely used to pry open can tops, (as shown in Fig. 3).

What I claim is:

1. A can opener comprising a body portion shaped to be grasped in the hand, and having an elongated slot, a longitudinally extended rod secured to the front end of the handle and extended lengthwise of the slot, the front end of the rod terminating in a 20 puncturing and guide member, a cutting disk rotatably and slidably mounted on the rod within said slot of the body portion, said disk being bodily movable along said rod in said slot from one end of the same 25 toward the other.

2. A can opener comprising a handle-like stamped metal body whose opposite edges are bent down to form side flanges, the forward end of the handle being tapered whereby to produce a restricted passage at such 30 end, the said body having a longitudinally extended slot, a rod having a pointed and hooked front end that seats in the restricted 35 passage at the front end of the handle, said rod extending lengthwise across the slot in the handle and having its inner end riveted 40

onto the handle body and a rotary cutter slidably mounted on the rod, said cutter including a cutting disk, a guiding disk, and a groove-like neck that joins the disks. 45

3. As an article, an implement of the character stated, comprising a stamped metal handle-like body, the opposite edges of which are bent down to form side flanges, said body having a longitudinal slot near the front end, the side flanges of the said front end forming a restricted passage, a flange that projects down from the front edge of the slot in the handle-like body, said flange having a concaved seat, the body having an aperture at the rear of the slot, a rod having its front end pointed and bent to form a guide and puncturing member, said front end being mounted in the restricted passage and held clamped by the opposite side flanges of the handle, the said rod also engaging the concaved seat in the front flange, the inner end of the rod being bent up and riveted over the aperture in the handle, and a rotary cutter slidably mounted on the rod and movable in the slot of the handle, said cutter including a cutting disk, a guiding disk and an intervening neck groove. 55 60 65

4. As an article, a device of the character stated, a handle-like body stamped from sheet metal, said body having side flanges, an elongated slot near the front end and a rotary cutter, and means for supporting the cutter in the slot in the body portion for rotary movement on its axis and sliding movement in the slot from one end of the same to the other. 70 75
